Louise K. Rhodes, 6835 E. Prairie Road,
Lincolnwood, Ill. 62659

Filed Nov. 3, 1969, Ser. No. 19,882

Term of patent 14 years

Int. Cl. D15—07

U.S. Cl. D49—13

In the drawings:

FIG. 1 is a front perspective view illustrating my new hand scrubbing implement;

FIG. 2 is a side elevational view of the hand scrubbing implement;

FIG. 3 is a top view of the hand scrubbing implement;

FIG. 4 is a front end elevation of the hand scrubbing implement;

FIG. 5 is a rear end elevation of the hand scrubbing implement; and

FIG. 6 is a bottom view of the hand scrubbing implement.

Broken lines illustrated in the above FIGS. 1 through 6 are for the purposes of disclosing environmental structure only and do not form part of the design.

I claim:

The ornamental design for a hand scrubbing implement, substantially as shown and described.
